US00D932163S

(12) **United States Design Patent** (10) Patent No.: **US D932,163 S**
(45) Date of Patent: **** Oct. 5, 2021**

(54) **SHOE**

(71) Applicant: **Reebok International Limited**, London (GB)

(72) Inventor: **John Greenhalgh**, Foxboro, MA (US)

(73) Assignee: **Reebok International Limited**, London (GB)

(**) Term: **15 Years**

(21) Appl. No.: **29/710,796**

(22) Filed: **Oct. 25, 2019**

Related U.S. Application Data

(60) Continuation of application No. 29/628,932, filed on Dec. 8, 2017, now Pat. No. Des. 868,441, which is a continuation of application No. 29/554,582, filed on Feb. 12, 2016, now Pat. No. Des. 807,001, which is a division of application No. 29/476,545, filed on Dec. 13, 2013, now Pat. No. Des. 749,310.

(57) **CLAIM**

The ornamental design for a shoe, as shown and described.

DESCRIPTION

FIG. 1 is a bottom perspective view of a shoe showing the claimed design;

FIG. 2 is a bottom view thereof;

FIG. 3 is a side view thereof;

FIG. 4 is another side view thereof;

FIG. 5 is a front view thereof;

FIG. 6 is a rear view;

FIG. 7 is a bottom perspective view of another embodiment of a shoe showing the claimed design;

FIG. 8 is a bottom view thereof;

FIG. 9 is a side view thereof;

FIG. 10 is another side view thereof;

FIG. 11 is a front view thereof; and,

FIG. 12 is a rear view.

The broken lines in the figures show portions of the shoe that form no part of the claimed design.

1 Claim, 10 Drawing Sheets
